UNITED STATES PATENT OFFICE.

MICHAEL MARTINEK, OF LYONS, ILLINOIS, ASSIGNOR TO WESTERN WIRE & IRON WORKS, INC., OF CHICAGO, ILLINOIS, A CORPORATION OF ILLINOIS.

SLIDING-DOOR LOCK.

Application filed March 7, 1927. Serial No. 173,402.

This invention relates to locks and more particularly to locks applied to sliding doors.

Among the objects of the invention are these: to provide a neat and efficient lock structure, which will automatically lock when the parts are brought together, which may be unlocked by a key from the outside and by a manually operated hand knob from the inside; a lock structure adapted to be morticed into a door; a device which, when unlocked, will present no projection, such as a handle-knob, on its inner face, and no parts projecting from its edge to catch or tear the clothing of the person passing through the open doorway; and one which has the key-hole of the tumbler lock so arranged as to avoid heretofore objectionable features, including entrance therein of foreign substances which clog and make the tumblers inoperative.

These and other objects, and the advantages of the invention will more fully appear as I proceed,—the invention consisting of the parts and combination of parts illustrated and described and more particularly pointed out in the claims hereto appended.

In the drawings:

Figure 1 is a side elevation of a portion of a door with a lock embodying my invention applied thereto.

Figure 2 is a side elevation of the portion of the door jamb with which the door operates.

Figure 3 is a transverse, sectional view of the door and lock, the section being taken in the planes of the dotted line 3—3 on Figure 1.

Figure 4 is a transverse, sectional view of a part of the door jamb, the section being just above the keeper plate and on the line 4—4 of Figure 2.

Figure 5 shows the parts illustrated in Figures 3 and 4, when brought together in locked relation.

Figure 6 is a perspective view of the keeper plate on the door jamb.

Figure 7 is a view in elevation of the inside of the lock, showing the parts in locked position.

Figure 8 is a similar view showing the same parts in the unlocked position, when actuated by a knob on one outside face of the lock.

Figure 9 is a similar view showing the same parts in the unlocked position when

actuated by a key inserted into the lock from the opposite side of the lock.

Figure 10 is a transverse, sectional view of the lock, the section being taken in the horizontal plane indicated by the dotted line 10—10 on Figure 9; and

Figure 11 is a longitudinal sectional view of the lock, the section being taken in the vertical plane indicated by the dotted line 11—11 on Figure 9.

Figure 12 is a sectional view of a detail.

In said drawings, a door is indicated at A, a door jamb at B, the lock as a whole at C, and the keeper, as a whole, at D.

The lock comprises two casing plates 1, 2, secured together by screws (not shown) or in any suitable manner, and spaced apart by side and end flanges 4, so as to form, together, a complete housing for the working parts.

The plate 1 is formed with an annular depression 5 in one face, near one end, and its wall is centrally apertured at 6 to receive the stem 7 of a knob 8. The knob is located in the depression 5. An operating member or wing 9 in the casing is mounted upon the knob stem 7 and secured thereto by a screw 10 or other convenient means, whereby the knob on the outside of the lock, when turned, will actuate the wing 9 on the inside of the lock.

The casing plate 2 is provided with an apertured hub 11, in which is secured by screw threads or other convenient means, a lock indicated as a whole at 12, provided with one or more movable wings 13 within the casing, and actuated by the insertion of a suitable key into the keyhole 14 of the lock 12.

Within the casing and in spaced apart relation are a pair of hooked-end lever arms 15, 15, whose action is that of a lever of the second class, each arm being mounted at one end over a pivot or fulcrum post 16.

The forward ends of the lever arms 15 are provided with inwardly facing keeper engaging hooks 17, 17, which are adapted to engage the shoulders 18, 18, on the opposite sides of the keeper D when the lock C and keeper D are brought into operative engagement, as indicated in Figure 7. Suitable tension means are employed to cause the lever arms 15, 15, to assume the closed or normal position shown in Figure 7; in this instance, the means employed are a pair of 110

2
springs 19, 19. Through one wall of the side flange 4 of the casing, that is through the edge of the lock C, is a longitudinally disposed opening 20 through which the hooked ends 17 of the lever arms 15 project in position to be engaged by the keeper D.

Secured to the inside of the casing and preferably to the inside of the plate 1, is a transversely disposed bolt or stud 21, upon which are mounted, in superposed relation, independently acting cam arms 22 and 23, capable of pivotal movement about the stud 21. The arm 22 is provided at its forward end with a detent or tappet 24 adapted to engage the inside margin of one arm 15, and is provided also with a cam portion 25 adapted to engage the inside margin of the other arm 15. The rear portion of the arm 22 is adapted to be engaged by the key actuated wing 13, a shouldered flange 25^a being provided for that purpose. When the wing 13 is rotated, the flanged end 25^a is moved so that the arm 22 swings about the pivotal stud 21. When power is applied to the two lever arms 15, 15, by the movement of the tappet 24 against one arm and the cam 25 against the other arm, said levers are moved in opposite directions, from the locked position shown in Figure 7 to the unlocked or open position shown in Figure 9.

The arm 23 is provided at its forward end with a detent or tappet 26, adapted to engage the inside margin of one of the lever arms 15, and is provided also with a cam portion 27 adapted to engage the inside margin of the other arm 15. The rear portion of the cam arm 23 is provided with a cam portion 28 adapted to be engaged by the knob actuated wing 9. One of the lever arms 15 is provided with an elongated recess at 29 and the part of the cam arm 23 which carries the cam 28 extends in the recess 29 and transversely of the lever 15. The thickness of the arms 22 and 23 which are shown in superposed pivotal position about the stud 21 is such that when the wing 9 actuates the cam 28, the cam arm 23 alone acts as power through the cam 27 and detent 26 to spread apart the levers 15, 15, and release the keeper D, and when the wing 13 actuates the flanged shoulder 25^a, the cam arm 22, through cam 25 and detent 24, acts as power to spread apart the arms 15, 15.

Referring again to Figures 1 to 6, inclusive, it will be understood that I have illustrated my improved lock C as applied to that type of doors where the door slides toward the door jamb in a different but adjacent vertical plane from the plane of the door jamb. Such an arrangement is commonly and desirably used in the case of sliding doors for bank tellers' cages, where it is desirable to secure the keeper D to the door B in the channel of a suitable metal keeper 30, which in the instance shown is provided with an

attaching flange 31 morticed into the edge of the door as shown in Figure 6, and suitably secured thereto by screws 32 or other suitable means. It will be noticed that the outer edge of the keeper D is inside of the vertical plane of the flange 31. The channel member 30 will of course be of sufficient width to accommodate the door A, in which the lock C is morticed, and of sufficient depth to permit the hook ends of the lock arms 15 to engage with and clasp in locking relation the keeper D, when the door is brought up to the door jamb, as clearly shown in Figure 5.

In bank tellers' cages, the sliding doors usually have limited movement, providing limited space for persons to pass between the door edge and the door jamb. It is therefore essential that the lock and keeper have no projecting parts which may catch and tear the clothing of persons passing through the door opening. The device of the present invention is exceedingly efficient in this respect.

It will be observed by reference to Figure 12, that the lock 12 is positioned so that the key 34 may be inserted with its long plain edge 35 down and guided by the lower straight portion 36 of the key hole 34, and its fluted tumbler-engaging edge 37 uppermost. This is possible because of the arrangement of parts and their location as shown and described, whereby the position of the tumblers will always be in workable condition.

Assuming the door and door jamb are in the position shown in Figure 5, the person desiring to open the door from the outside will insert the key in the lock 12, thereby operating the tumbler wing or wings 13, and through the action above described, the cam arm 22 will spread apart the lever arms 15, 15, as indicated in Figure 11, thus disengaging the lock ends 17 from the keeper D, enabling the person to slide the door A away from the door jamb B and effect an entrance. The door being again closed, in the position shown in Figure 5, the person being on the other side, and desiring to open the door, will take hold of the knob 8, slightly turn it to actuate the wing 9, and through the cam arm 23, spread apart the arms 15, 15, into the disengaged position shown in Figure 8, and then slide the door away from the jamb.

I claim as my invention:

1. A sliding door lock comprising a keeper member and a casing member, the casing having an opening in one edge and provided interiorly with a pair of lever arms having their movable ends adapted for operative locking engagement with the keeper member, means for holding said arms normally in the locked position, a key actuated device secured to one side of the casing and a knob actuated device secured to the other side of

- the casing, a pivot in the casing between the lever arms, two lever devices mounted movably in superposed relation upon said pivot, and each adapted to engage and spread apart both lever arms, a wing member connected with the knob actuated device to contact with and actuate one of said pivoted lever devices independently of the other pivoted actuating device.
- 5 10 2. A sliding door lock comprising a keeper member and a casing member, the casing having an opening in one edge and provided interiorly with a pair of lever arms having their movable ends adapted for operative locking engagement with the keeper member, means for holding said arms normally in
- the locked position, a key actuated device secured to one side of the casing and a knob actuated device secured to the other side of the casing, a pivot in the casing between the 20 lever arms, two lever devices mounted movably in superposed relation upon said pivot, and each adapted to engage and spread apart both lever arms, a movable member of the key actuated device having operative connection with one of the pivoted lever devices to actuate the same independently of the other lever device.
- 15 10 In testimony that I claim the foregoing as my invention I affix my signature, this 25 2nd day of March, 1927.

MICHAEL MARTINEK.
